CLAIM

The ornamental design for a computer screen with an icon, as shown and described.

DESCRIPTION

FIG. 1 is a front view of an icon for a computer screen, on an enlarged scale; and,

FIG. 2 is a front view thereof, on a greatly enlarged scale. The broken line drawing of a computer screen in both views is for illustrative purposes only and forms no part of the claimed design.

1 Claim, 2 Drawing Sheets

FIG. 1

FIG. 2
